[57] **CLAIM**

The ornamental design for a sunshade for an infant's car seat, as shown and described.

DESCRIPTION

FIG. 1 is a front perspective view of a sunshade for an infant's car seat showing my design.

FIG. 2 is a left side view thereof.

FIG. 3 is a rear view thereof.

FIG. 4 is a front view thereof.

FIG. 5 is a further perspective view thereof, taken from a different side than that of FIG. 1, and the sunshade for an infant's car seat being partially folded.

The broken lines indicating an infant's car seat in FIGS. 1-5 have been shown for illustrative purposes only.

FIG. 1

FIG. 4

FIG. 2

FIG. 5

FIG. 3
